POLARIZING MICROSCOPE ATTACHMENT

John T. Armbruster, Niagara Falls, N.Y., assignor to
American Optical Corporation, Southbridge, Mass.

Filed July 14, 1975, Ser. No. 595,828

Term of patent 14 years

Int. Cl. D16—06

U.S. Cl. D16—58

Fig. 3

Fig. 4

Fig. 5

FIG. 1 is a perspective front view of a polarizing microscope attachment embodying my new design;

FIG. 2 is a plan view from one side of the microscope attachment;

FIG. 3 is a plan view from the top of my microscope attachment;

FIG. 4 is a front plan view of the microscope attachment; and

FIG. 5 is a rear plan view of the microscope attachment.

I claim:

The ornamental design for a polarizing microscope attachment, as shown and described.
